UNITED STATES PATENT OFFICE.

LUTHER WATSON HOLLAND, OF PLEASANT HILL, MISSOURI.

LATCH.

1,383,302.

Specification of Letters Patent.

Patented July 5, 1921.

Application filed May 20, 1920. Serial No. 382,946.

To all whom it may concern:

Be it known that I, LUTHER W. HOLLAND, a citizen of the United States, and a resident of Pleasant Hill, in the county of Cass and State of Missouri, have invented a new and useful Improvement in Latches, of which the following is a full, clear, and exact description.

My invention relates to improvements in latches, and it consists in the combinations, constructions and arrangements herein described and claimed.

An object of my invention is to provide an improvement over that form of latch set forth in my pending application, Serial No. 182,410, filed July 25, 1917.

In said application a latch is disclosed having a bell-crank lever, one end of which is formed into a latch plate and is arranged to enter between a latching lug carried by a strike plate, which enters an opening in the casing, and one wall of the casing. I have found that in the operation of the latch mentioned in the aforesaid application, the edge of the bell-crank lever is apt to wear. Furthermore, it must be raised against the tension of the spring whenever the door is closed. This may necessitate slamming the door.

An object of the present invention is to obviate the necessity of slamming the door in order to insure its latching. In overcoming this objection, I make use of a slidable latching dog which projects normally in such a position that it may be engaged by the latching lug so that the weight of the dog alone is raised prior to the engagement of the latch to hold the door closed.

A further object of my invention is to provide a latching dog which may be made thicker than the bell-crank lever, so that if the latch is put on slightly out of alignment with the lug on the strike plate, it will still catch.

A further object of my invention is to provide a removable latching dog which may be case-hardened, thereby prolonging the life of the latch.

Other objects and advantages will appear in the following specification, and the novel features of the invention will be particularly pointed out in the appended claims.

My invention is illustrated in the accom-

panying drawings, forming part of this application, in which—

Figure 1 is an inside face view of the latch in its closed position,

Fig. 2 is a section along the line 2—2 of Fig. 1,

Fig. 3 is a top edge view,

Fig. 4 is a view similar to Fig. 1 and showing the latch open,

Fig. 5 is a section along the line 5—5 of Fig. 4, and

Fig. 6 is an isometric view of a portion of the strike plate and casing,

Fig. 7 is an end elevation of the lock.

In carrying out my invention, I provide a metal frame 1 which has one side thereof bent up to form a flange 2. At 3 I have shown a rectangular cut-away portion having a portion 4 bent up to form a strengthening flange. The opening 3 registers with an opening 5 in the flange 2, of the shape shown in the drawings.

Struck up from the plate 1 are arc-shaped flanges 6 and 7 forming journal members for the circular portion 8 of the bell-crank lever. One arm 9 of the bell-crank lever constitutes a handle, and the other arm 10 extends toward the flange 2, as shown in the drawings. The circular portion 8 of the bell-crank lever is preferably provided with a square opening 11 arranged to receive the squared shank of a knob 37. The bell-crank lever is also provided with an arc-shaped slot 12. A circular cap 13 is provided which has flanges 14 arranged to enter corresponding openings in the plate 1, the flange being upset or turned back so as to secure the cap to the plate. A flange 15 enters the arc-shaped opening 12 in the bell-crank lever to limit the movement of the lever in either direction.

Mounted to slide on the plate 1 is a latching dog 16 having a cut-away portion 17 in which the end of the arm 10 of the bell-crank lever plays. The bottom portion of the dog 16 is beveled, as shown at 16^a, and is also rounded for a purpose explained later. A guide housing 18 is provided for the latching dog 16, this guide housing having lugs or flanges 18^a arranged to enter a corresponding opening in the flange 2, these flanges or lugs being upset to secure the housing to the flange 2. Similar lugs or

flanges 19^b enter openings in the plate 1 and are secured to the plate. The housing is slotted as shown at 20 to permit the arm 10 of the bell-crank lever to move freely.

- 5 A detent 21 of the shape shown in the drawings is provided with laterally bent portions 22 which enter an L-shaped opening in the plate 1. The detent 21 is bent away from the plate at 23 and extends over the 10 arm 10 of the bell-crank lever, being bent downwardly at 24 to form a shoulder.

At 25 I have shown a flange which is struck up from the plate 1 and to which is secured a spring 26, the outer end of the 15 spring resting on the detent 21. A similar spring 27 is fastened to the plate 1 at 28, the free end of the spring bearing on the arm 10 of the bell-crank lever.

From the foregoing description of the various 20 parts of the device, the operation thereof may be readily understood. The strike plate 29 has formed thereon a latching lug 30 and is secured to the door frame. Let us assume that the door is open. The 25 latching dog 16 has its end 16^a projecting slightly below the upper edge of the opening 3 for an eighth of an inch or so. It will be observed that the bell-crank lever is held by the shoulder 24 of the detent. When the 30 door is closed, the latching lug enters the openings 3 and 5 and engages the latching dog, pushing the latter upwardly. Now when the extension 22 of the detent engages the strike plate, it will push the detent inwardly against the tension of the spring 26 until it clears the arm 10 of the bell-crank lever, whereupon, the latter will force the latching dog 16 into the space 31 between the latching lug 30 and the inner face of the 35 plate 1, thus holding the door securely to the frame.

When it is desired to open the door, the handle 9 is pulled. The arm 10 of the bell-crank lever will engage the latching dog 16 40 and will lift it out of engagement with the latching lug 30, and the bell-crank lever will be held by the engagement of the shoulder 24 of the detent on the underside of the arm 10 as soon as the door is opened. The 45 door may now be latched again by merely closing it in the ordinary manner. It will be seen that the wear comes on the latching dog which may be made of any suitable thickness. Furthermore, the end of the dog 50 is beveled and rounded so that even though the latch or strike plate may be placed out of alignment, the latching dog will still engage the latching lug 30, which it might not do if it were made of thin material. 55 When the door is first closed, the latching dog is lifted by the latching lug 30, not against the tension of the spring, but merely against its own weight, which is negligible, since the provision of the cut-away portion 60 17 in the dog permits the upward movement

of the latter independently of the lever arm 10.

A flange 15 on the cap 13, which projects through the slot 12 in the lever, limits the movement of the lever in both directions. 70 This cap is provided with a central opening 35 through which a shank 36 of a knob 37 may project, the shank 35 entering the squared opening 11 in the lever, so that the latter may be operated either by the handle 75 9 or by turning the knob 37. The cap 13 serves a double purpose. It is secured to the casing wall outside of the flanges 6, so that it does not interfere with the movement of the lever, but it has a portion which overlies 80 the circular portion of the lever, thereby preventing the lever from being unseated. The cap also obviates the necessity of a cover, such as that ordinarily used on latches, thus reducing the expense in manufacturing the device. 85

A nut 38 fits on the threaded end of the shank 36 and is arranged to pass through the opening 35 in the cap 13 in close engagement with the circular portion of the bell-crank lever. This holds the knob in position, but at the same time permits the bell-crank lever to move freely in its journals. 90

I claim:

1. The combination with a strike plate 95 having a latching lug, of a latch having a casing provided with an opening arranged to receive the lug, a movable latching dog having a portion arranged to enter between the lug and the casing of the latch, and a movable handle having a portion arranged to engage said latching dog to move it out of engagement with the lug, said dog being adapted to move relatively to said handle, and a spring for forcing said lever into engagement with the latching dog. 100

2. The combination with a door jamb having a latching lug, of a door provided with a latch, said latch having a casing provided with an opening arranged to receive said 110 latching lug, a slidable dog having a portion arranged to enter between the lug and the casing, a pivoted lever having a portion arranged to move into engagement with the latching dog to force the latter out of engagement with the lug, a spring for forcing said lever into engagement with the latching dog, and a spring pressed detent for holding said lever against the tension of its spring to permit the latching dog to 115 have a movement independent of said lever. 120

3. The combination with a door jamb having a latching lug, of a door provided with a latch, said latch having a casing provided with an opening arranged to receive said 125 latching lug, a slidable dog having a portion arranged to enter between the lug and the casing, said dog having a cut-away portion, a pivoted lever having a portion arranged to enter the cut-away portion of the 130

dog whereby the dog is permitted a movement independent of the lever, a spring arranged to bear on said lever and tending to force the lever into engagement with the 5 dog, a spring pressed detent having a portion adapted to engage the lever to hold the latter against the tension of its spring, and means carried by the detent for releasing the latter when the door is closed.

10 4. The combination with a door jamb having a latching lug, of a door provided with a latch, said latch having a casing provided with an opening arranged to receive said latching lug, a slidible dog having a portion arranged to enter between the lug and the casing, said dog having a cut-away portion, a pivoted lever having a portion arranged to enter the cut-away portion of the dog, whereby the dog is permitted a movement independent of the lever, a spring arranged to bear on said lever and tending to force the lever into engagement with the 15 dog, a spring pressed detent having a portion adapted to engage the lever to hold the latter against the tension of its spring, an extension carried by said detent and arranged to project through the casing for engaging the door jamb to release the detent when the door is closed.

20 5. The combination with a strike plate having a latching lug, of a latch having a casing provided with an opening, a latching dog slidible on the casing with respect to said opening, said dog having a beveled lower end and being provided with a cut-away portion, a lever pivotally mounted on said casing and having one end projecting into the cut-away portion of said dog, a guide housing for said latching dog secured 25 to said casing and having a slot to receive the lever, a spring for normally forcing said lever downwardly, a spring pressed detent arranged to engage said lever to hold the

lever against the tension of its spring, said detent having a portion arranged to pass 45 through the casing to the outside thereof, whereby said detent may be moved to release said lever.

6. In a latch a casing, a lever having a portion formed on the arc of a circle, flanges 50 carried by said casing and forming journals for the circular portion of the lever, and a cap secured to said casing for holding said journaled lever in position.

7. In a latch a casing wall, opposed arc-shaped flanges carried by said casing wall, a lever having a substantially circular portion journaled between the opposed arc-shaped flanges, and a cap secured to said casing exteriorly of said arc-shaped flange 60 and having a portion arranged to overlie the circular portion of the lever to hold the latter in position.

8. In a latch a casing, a lever having a portion formed on the arc of a circle, flanges 65 carried by said casing and forming journals for the circular portion of the lever, a cap secured to said casing for holding said journaled lever in position, and a door knob operatively connected to said lever, said lever and said door knob being disposed on opposite sides of said casing.

9. In a latch a casing wall, opposed arc-shaped flanges carried by said casing wall, a lever having a substantially circular portion journaled between the opposed arc-shaped flanges, a cap secured to said casing exteriorly of said arc-shaped flanges and having a portion arranged to overlie the circular portion of the lever to hold the latter 75 in position, and a door knob operatively connected to said lever, said lever and said door knob being disposed on opposite sides of said casing.

LUTHER WATSON HOLLAND.
